[57] CLAIM

The ornamental design for a razor handle, substantially as shown and described.

DESCRIPTION

FIG. 1 is a rear elevational view of a razor handle showing our new design;

FIG. 2 is a front elevational view thereof;

FIG. 3 is a side elevational view, the opposite side being substantially a mirror image thereof;

FIG. 4 is a top plan view thereof; and

FIG. 5 is a bottom view thereof.
